UNITED STATES PATENT OFFICE.

JOHN GEORGE LEYNER, OF DENVER, COLORADO.

DIE FOR DRILL-MAKING MACHINES.

1,078,295.

Specification of Letters Patent.

Patented Nov. 11, 1913.

Original application filed March 25, 1912, Serial No. 686,133. Divided and this application filed April 13, 1912. Serial No. 690,585.

To all whom it may concern:

Be it known that I, JOHN GEORGE LEYNER, a citizen of the United States of America, residing in the city and county of Denver 5 and State of Colorado, have invented new and useful Dies for Drill-Making Machines, of which the following is a specification.

My invention relates to improvements in dies for drill-making machines; and the 10 objects of my invention are: First, to provide multiple and interchangeable part sets of die jaws for making die formed forgings of any and every kind and character that require one or more successive forging step 15 treatments to complete them. Second, to provide a set of multiple part intermeshing and interchangeable die jaws and formers and dollies that are especially adapted to form either locking lugs or collar portions on the 20 shank ends of and to size and otherwise form the shank end of rock cutting drill bits so that they will fit into the chucks of the rock drilling engines they are to be used in. And third, to provide operative sets of multiple 25 part interchangeable die formed forgings making half die jaws for use in die formed forgings making machines that are adapted to make forgings of any forging metal of any and all kinds and characters of articles that it is practical to make 30 in the form of a forging. I attain these objects by the mechanism illustrated in the accompanying drawings, in which:

Figure 1, is a side elevation partly in section, of a drill forming and sharpening machine equipped with the multiple part die jaws embodying my invention. Fig. 2, is a plan view of the anvil portion of the machine, showing one of the multiple part die 35 jaws, the dolly driving engine being omitted. Fig. 3, is a perspective view of a one half part of a multiple die carrier in which is secured one of the roughing and finishing dies, a pair of each being employed. Fig. 4, is a transverse sectional view of Fig. 3, on the line 4—4. Fig. 5, is a perspective view of the shank end former. Fig. 6, is a side view of the upsetting dolly. Fig. 7, is a side view of a drill bit, illustrating the 50 first step in forming the locking lugs thereon. And Fig. 8, is a side view of a completed drill bit.

Similar letters of reference refer to similar parts throughout the several views.

55 Referring to the drawings: The numeral

1 designates a column that forms the foundation base of an operative drill sharpener hereinafter termed the base. This column form of base is provided with a floor flange 2 and with a cylinder bore 3, and at its top end 60 a cylinder 3^A is secured to it in any suitable manner. The top of this cylinder 3^A is provided with an anvil portion 4, and above the anvil a hammer block 5 is reciprocally mounted on bolts or rods 6 that are connected at one of their ends to the hammer block and that extend slidably down through the anvil and are secured at their opposite ends to the upper end of a piston head 7, that is reciprocally mounted in a cylindrical 70 bore 3^B, formed in the cylinder 3^A. The bolts or rods 6 preferably extend down through the piston head and are secured to it by nuts 9.

The piston head is preferably a differential ended piston, the upper end 7 being of disk form, and from this disk-shaped end a stem portion 8 depends into the cylinder 3, of the base. The disk portion and also the stem portion are provided with packing 80 rings 8^A. A throttle valve 10, which may be of any suitable multiple port type, and which is provided with a handle 10^A, is secured to the side of the machine and is arranged to admit compressed air by a pipe 11, to the 85 lower end of the piston head to raise it in its cylinder and to its upper end, through suitable ports, to move it down in its cylinder alternately, which reciprocal movement of the piston imparts reciprocal movements 90 to the hammer block, which is so relatively connected to the stroke of the piston head in its cylinder and to the top forging surface of the anvil that it reciprocates vertically above it in hammer blow striking relation to 95 it, and the opposing faces of both the anvil and the hammer block are arranged to receive either interchangeable drill bit forming, sharpening and shanking die jaws, or shanking die-carriers 11^A and 11^B, as illustrated in Figs. 1 and 2, and also die carriers for making other kinds of die formed forging work. These die carriers are held in recesses formed in the anvil and hammer block by bolts 11^C and 11^D, which are arranged in slots to clamp the jaws in their recesses. The upper bolt 11^D is secured against dropping out of its recess when loosened by an expansive spring 11^E, which holds it by pressure in its slot.

A more complete description of a machine embodying the above mentioned elements is given in my pending application, Serial Number 686,133, filed March 25, 1912, of which my present application is a divisional part.

An arm 12 projects from one side of the cylinder 3^A far enough to form a support for an engine cylinder 13, which is slidably mounted thereon in axial alinement with the longitudinal axis of the die jaws of the vise. This cylinder is arranged on the supporting arm to be moved reciprocally to and from the vise jaws and it is also arranged to be clamped rigidly to the support when set in its dolly operating position. There are several ways in which the engine cylinder may be "adjustably secured" and reciprocally moved on the supporting arm. My present invention can be combined with any kind of co-operating cylinder and piston that is arranged to reciprocally drive and upset the ends of drill steel, with dollies and formers and other character of dies that are adapted to work against the ends of steel or iron bars or pieces of any forging metal. This dolly driving cylinder 13 has a valve chest 14, which is connected with the throttle valve chest 10, by a hose 15. In the engine 13, an upsetting dolly 16 is mounted, in operative relation to the die-carriers 11^A and 11^B, of the anvil and hammer block, as will be fully shown hereinafter.

The engine 13 is slidably mounted on a slideway 17, which is formed on the arm 12, that projects from the cylinder 3^A, and it is provided with a feed screw 18, to which a handle 19 is secured, by which the cylinder may be moved back and forth on its slideway, far enough from the vise jaws, to permit a dolly to be inserted in the guide flange 20, of the engine, or to be removed from it when desired.

The engine is provided with clamping bolts 21, by which it may be clamped in adjusted positions rigidly to its slideway. The dolly is driven on its forward strokes by a hammer piston that is reciprocally mounted in the cylinder of the engine, and that is actuated by the air flowing through the hose 15, from the throttle valve 10, as is well understood, and in a manner that is common to several of the dolly driving engines, of machines in common use. The dolly is moved on the rearward strokes of its reciprocal movement by a spring 22, as shown.

As illustrated, the die-carriers 11^A and 11^B are arranged and adapted for forming the shank or drill chuck holding ends of rock cutting drill bits 23 used in rock drilling engines for drilling holes in rock by forming collars 24 or lugs 25 on them, as shown in Figs. 7 and 8, which operation is fully described hereinafter. I have, however, illustrated a set of multiple part die jaws for

forming the shank ends of rock cutting drill bits, inasmuch as the die jaws and the former and upsetting dollies illustrated were especially designed for die forging the particular character of locking lugs and shank ends of drill bits illustrated in Fig. 8.

The term shanking a drill steel, means to so form, size, and shape one end of a bar of drill steel that is to be made into a drill bit, that it fits into the kind of chuck it is to be held by, of the rock drilling engine it is to be used in and driven by. I preferably use a pair of oppositely arranged chuck locking lugs 25 on the shank end of the drill bit, and also size the terminal end portion of the shank end of all drill bits so that they will fit closely in and can be instantly inserted and withdrawn from the chuck of the rock drilling engine they are to be used in.

In order to properly form, shape, and size lugs as well as the whole length of the chuck fitting shank end of the drill bit, I employ a separate and different set of half die-carriers 11^A and 11^B, from those used for forming and sharpening the rock cutting lips on the opposite ends of the drill steel from their shank ends. A perspective view of one of these carriers with its dies is shown in Fig. 3. These two half shanking die-carriers 11^A and 11^B are formed with dove-tailed shouldered portions 26, that are arranged to fit into the dove-tailed locking recesses 27 of the anvil and hammer block, and they are also arranged and adapted to be secured in those recesses by the clamping bolts 11^C and 11^D respectively.

They extend entirely across and beyond the top surfaces of the anvil over its shelf portion 28 and also beyond the die surface of the hammer block over its shelf portion, and they rest and are supported on the blocks 29 which are clamped on the shelf portions by plates 30 and bolts 31. These carriers comprise semi-circular shaped half round members that are each provided with a semi-circular or half round die groove or recess 32, that extends throughout its length, except at its rear end, where a narrow terminal end portion 33 is formed, of enough smaller diameter than the recess 32 to form a shoulder 34.

These carriers form supports for half part dies, that make up the rest of this shanking set of dies, and they are placed inside of them as follows: In the rear end and central portion of the length of each of the carriers, I place and secure a half round roughing and finishing die forming bushing die 34^A. These half round roughing and finishing dies are secured in the rear end of the semi-circular recess of the carriers against the shoulder 34,

and they may be secured in any suitable manner. I preferably, however, secure them by pins 35 which I term locking pins, and which extend through the bottom portion of 130

each half die at its rear end, and also through the bottom of each of the carriers. These apertures in which these pins fit are slightly counter-sunk at their outer ends, 5 and the ends of the pins are upset or slightly riveted in these counter-sunk ends. This arrangement affords a simple way of securing this rear end of the roughing, sizing, and finishing die in the carriers, and at the same 10 time permits of their removal wherever desired by simply driving out the locking pins. The forward ends of these roughing and finishing half dies are preferably arranged to slide and thus to lock under projecting ribs 36 which are formed along the 15 opposite side edges of each of the carriers, the under side edges of which are beveled, and the edges of the opposite sides of each half of these roughing and finishing dies 20 are likewise chamfered or beveled off and are arranged to register with and to fit closely under the ribs of the carriers. These roughing, sizing and finishing dies are consequently removably secured in a stationary 25 position in the carriers, and each of them contains a roughing portion 37 which is a flattened portion containing a slight central circular shaped recess 38 at its rear end, in which the round body of the drill steel 30 fits, and a larger semi-circular portion 39 which is formed adjacent to this flattened roughing portion, receives and defines the height or the length of the lugs above the body of the drill steel, and consequently defines the diameter of drill steel through the 35 lugs, and on the opposite side of this circular lug defining part 39 a flattened finishing portion 40 is formed, adjacent to which a circular recess portion 41 is formed, that 40 ends in an outwardly flaring, tapering, upsetting terminal end portion 42 at the opposite end of the bushing from its roughing portion, and that is adapted to size and straighten and finish the terminal end of the 45 shank portion of drill bits. These two roughing finishing half dies occupy the rear end and central portion of the shanking jaws, leaving a space in the front end of the shanking jaws in which a pair of semi-circular 50 shaped upsetting plunger moving half jaws 43 are fitted. Each of these upsetting plunger moving jaws is provided with a semi-circular recess 44 that extends throughout its length from one end to near its opposite end which is solid and flat across its top, and has a square end, and this solid or closed end is placed opposite to the upsetting dolly 16 which is placed in the guide flange 20 of the dolly driving engine. The 55 opposite side edges of each of these upsetting plunger dies are provided with beveled edges 44A that are adapted to fit slidingly and reciprocally under the projecting ribs 36 of the die-carriers, and they have a sliding movement back and forth out of and back

into the front end of the carriers, the lower upsetting plunger half jaw striking when pushed out of the front end of the carrier, the front end of the upsetting dolly 16, and the upper upsetting and plunger die jaw is 70 pushed when the member 6 is raised against a stop arm 45, that is secured to one end of a rod 46, the opposite end of which extends into an aperture formed in a lug on the forward end of the hammer piston cylinder, in which the rod is secured by a set screw, not shown. This stop arm is set to stop the upper upsetting die when even with the face of the upsetting dolly, when it is shouldered back against its guide flange 20. 80 This upsetting dolly is provided with a spring receiving recess 47 similar to that of the drill bit forming dolly, which is arranged to receive one end of the spring 22, which is arranged to assist the upsetting 85 dolly on the backward return stroke of its reciprocal movement as it strikes against the ends of these two upsetting plunger half die jaws, and drives them slidingly into the die-carriers, as will be presently described. These upsetting plunger die jaws are adapted to receive the heated end of the bars of drill steel that are to have shank ends formed on them, after these die jaws are pushed out of the carriers, against the 90 end of the upsetting dolly and of the stop arm 45, by the operator. The end is then upset to form a collar, as will be presently described. In case hollow drill steel is used, a shank end former 48 is employed, 95 to upset the end of the shank and to enter and keep open the end portion of the axial aperture through the drill steel. This shank end former comprises a head portion 49, provided with an axially positioned projecting round lug 50, that tapers smaller from its base to its end, and that is adapted to enter and slightly enlarge and outwardly flare the entrance end of the axial aperture of the drill steel. This projecting lug preferably projects from the bottom of a sunken recess 51 that is formed in the face end of the head portion, that is made of a diameter to receive the size of drill steel being worked, and confine its extreme end. The 100 head portion of this shank end former is provided with a shank end 52 that is made to fit closely but loosely in the die recesses of the upsetting plunger die jaws, and of a length to fit against their closed ends, 105 and allow the inside of the head portion to rest against their ends and project beyond them, and to thus lie in the semi-circular recess of the shanking die jaws, opposite to the adjacent end of the roughing jaws. 110 This shank end former is adapted to be used solely in these upsetting plunger jaws, and is not intended to be used in the guide flange of the dolly driving engine. These shank, roughing, finishing, upsetting, and 115

plunger and shank end dies, make a complete set of dies for forming lugs on and for the shank ends of bars of drill steel, that have to be provided with oppositely arranged chuck receiving locking lugs.

- The operation of die forging and forming the chuck locking lugs, and of sizing and finishing them, as well as the terminal shank ends of the drill steel, is as follows: The 10 drill bits are cut from merchantable bars of either hollow or solid drill steel to the lengths of the drill bits required, and the ends selected for the shanking ends are heated to a forging heat. Then, assuming 15 that the shanking and roughing and finishing dies, and also the upsetting plunger jaws, have been properly positioned, and that the upsetting plunger jaws have been pushed out against the stop arm, and the 20 end of the upsetting dolly, the end of a heated drill steel is placed in the die recess of the lower upsetting plunger die jaw against its closed end, the throttle valve is then manipulated to close the upper die 25 jaws down tight on the drill steel, which also causes the upper roughing and finishing die to also grip the drill steel, and these two sets of jaws are so relatively arranged that the roughing and finishing jaws hold the 30 drill steel the tightest. The throttle valve is then thrown wide open, which starts up the reciprocating hammer action of the upsetting dolly against the closed ends of the upsetting plunger dies, which drives them 35 slidably into the carriers, and as there is a short clear space in the carriers between the inner end of the roughing and finishing dies, and these upsetting plunger dies, when they are pushed out of the front end of the 40 shanking dies against the end of this upsetting dolly, and of the stop wide arm, the heated drill steel along this clearance space between these two sets of dies is upset, as the upsetting plunger dies are driven into 45 the carriers by the reciprocating hammer blows of the upsetting dolly, which upsets a round collar 24 on the drill steel in the clearance space between these roughing and finishing dies and the upsetting plungers, 50 as shown in Fig. 7. The action of the dolly is then stopped, and the jaws are opened and the drill steel is drawn back far enough to place this collar portion on the roughing portion 37 of the roughing and finishing 55 dies, where it is subjected to a few hammer blows of the hammer block, and the upper half roughing and finishing die, which flattens the collar portion into two rough oppositely arranged lug portions. These are 60 then placed vertically in the lug's height defining circular space 39 adjoining the roughing die surface, and they are shortened to their proper height above the surface of the bar of drill steel. The lugs are 65 then placed on the finishing surface 40 of

the roughing and finishing die and a finishing pressure treatment is given to them. The upsetting and plunger dies are then again pushed out against the upsetting dolly and the stop arm, and the shank end former is then placed in them, and the drill steel is placed against the end of this former with its lugs in the lug height defining space. The vise is then closed and the dolly started up and operated until the upsetting and plunger and shank end former have been driven as far as they will go into the die-carriers, which action drives the tapered lug 50 into the axial aperture of the drill steel and also upsets and slightly enlarges and compresses the metal and sizes it at the shank end of the drill steel. The drill steel is then withdrawn and inserted in a drill holding chuck gage, that is exactly like the chuck the shanks fit in when inserted in a rock drilling engine, and if it enters freely and fits properly it is done. If, however, it sticks or binds at any part of its end or at or around or on its lugs, the operation, or enough of it, is repeated until the shank end 90 enters the drill holding chuck loosely and fits properly.

The above description applies to the shanking of round hollow drill steel, but either hollow or solid, hexagon, cruciform 95 or octagon steel can be as easily treated by substituting shanking, roughing, and finishing, and also upsetting plunger dies, especially formed to receive these shapes of steel. My invention, however, contemplates in this respect any combination of dies that will 100 form either a collar or a lug form of shank end on drill steel for use as rock cutting drill bits in rock drilling engines.

I have illustrated and described the preferred construction of a multiple part die embodying my invention. I do not wish, however, to be limited to the construction and arrangement shown, as changes might be made in design and arrangement, and even in the number of parts, without departing from the spirit of my invention.

Having described my invention, what I claim as new and desire to secure by Letters Patent is:

1. In a multiple part die, the combination of an anvil, a reciprocating hammer block, and a dolly engine, with a pair of shanking end forming die-carriers removably secured in said anvil and hammer block, a pair of bushing jaws removably fixed in said carriers, a pair of upsetting jaws reciprocally mounted against accidental displacement in said carriers, and a shank end former and a dolly arranged to coöperate with said carriers to form a shank end on a drill bit adapted to fit the chuck of the rock drilling engine in which it is used.

2. In a multiple part die for die-formed forgings making machines, a set of shanking

130

- die-carriers adapted for drill steel and provided with an axial aperture, a pair of shanking dies in said die-carriers, upsetting plunger dies in said die-carriers, a dolly arm 5 ranged to upset the shank end of a drill bit and form a collar thereon; means including a pair of finishing and sizing dies in said die-carriers for reducing this collar portion to oppositely arranged lug portions and 10 then to size and finish said lugs and shank end portions, and a second dolly to maintain the axial aperture at the shank end of said drill steel.
3. Multiple part die-carriers for drill 15 sharpening and die-formed forgings making machines, adapted to work drill steel and forge various articles; provided with an axial aperture, a set of shanking dies, a pair of upsetting plunger reciprocating dies and 20 an upsetting dolly arranged to upset the shank end of the hollow drill steel and form a collar portion thereon, roughing, sizing and finishing die surfaces for changing said collar portion to a pair of oppositely ar- 25 ranged lug portions, and a shank end former provided with an axially positioned projecting lug adapted to extend into and flar- 30 gingly enlarge the axial aperture of said drill steel.
4. In a multiple part die, a set of die-car- 35 riers comprising a pair of half part mem- bers provided with a bushing die having a roughing, finishing, and lug and shank and sizing dies, a pair of shank and upsetting 40 and plunger die jaws reciprocally mounted in said carriers, a shank end former dolly fitting in said upsetting and plunger dies, a dolly engine, an upsetting dolly recipro- cated by said dolly driving engine for driv- 45 ing said upsetting and plunger dies, and a stop arm arranged to gage the extent of movement of one of said pair of upsetting and plunger die jaws.
5. In a drill-making machine, die-carriers
- comprising hollow, elongated members hav- 45 ing inwardly projecting die-retaining ribs along the direction of their length.
6. In a drill-making machine, die-carriers comprising a pair of coöperating hollow semi-circular shaped members having in- 50 wardly projecting die-retaining ribs along their meeting edges.
7. In a drill-making machine, die-carriers comprising hollow, elongated members hav- 55 ing inwardly projecting die-retaining ribs along the direction of their length, and die- abutments at one end.
8. In a drill-making machine, a pair of die- 60 carriers comprising hollow, elongated members having inwardly projecting die- retaining ribs along the direction of their length, and coöperating dies in said carriers having beveled portions along the meeting edges adapted to engage the retaining ribs of said carriers.
9. In a drill-making machine, a pair of die-carriers, comprising hollow, elongated members, having inwardly projecting ribs, and a pair of coöperating upsetting-jaws in 65 said carriers, each comprising a hollow semi- cylinder closed at one end and having bevel- 70 ed portions along their meeting-edges adapted to engage the ribs of said carriers.
10. In a drill-making machine, a pair of coöperating semi-circular shaped dies, 75 adapted when closed to grip the drill-steel, and a pair of coöperating upsetting-jaws in alinement with said dies, each comprising a hollow-cylinder closed at the end farthest from said dies, and means for striking said 80 closed ends to reciprocate the upsetting-jaws against the drill-steel.

In testimony whereof I affix my signature in presence of two witnesses.

JOHN GEORGE LEYNER.
